United States Patent Office.

ROBERT O'BRIEN, OF TOWLESVILLE, NEW YORK.

Letters Patent No. 76,507, dated April 7, 1868.

IMPROVEMENT IN HARNESS.

The Schedule referred to in these Letters Patent and making part of the same.

TO ALL WHOM IT MAY CONCERN:

Be it known that I, ROBERT O'BRIEN, of Towlesville, in the county of Steuben, and State of New York, have invented some new and useful Improvements in Harnesses; and I do hereby declare that the following is a full, clear, and exact description thereof, which will enable those skilled in the art to make and use the same, reference being had to the accompanying drawings, forming part of this specification.

The present invention consists in so constructing the several parts of a harness for horses or other animals, with the collar or not included, that, by the pulling of a single strap, such harness can be opened and set free from the animal at any moment when so desired—the advantage and importance of which are obvious.

In the accompanying plate of drawings, my improvements in harnesses are illustrated—

Figure 1 being a plan or top view of a harness spread out, which harness is made according to the present invention, and

Figure 2 a central section taken in the plane of the line $z z$, fig. 1.

Similar letters of reference indicate corresponding parts.

A, in the drawings, represents the bridle portion of the harness, to which B are the blinders, secured or affixed to the cheek-straps C.

The upper end of each of the straps C is looped, and in such loop a metal plate, D, hung, that at their outer ends are hinged together, turning upon a pintle, E, that extends through the upright guide-pieces F to a plate, G, that, when the bridle is on, rests upon the top of the head.

E², a spring, on pintle E.

This pintle E terminates at one end in a loop, H, to which is hung one end of a strap, I, that, at its outer end, is hung to a loop, J, of a pintle, K, extending loosely through the outer ends of a bracket-arm, L.

M, a spring, on pintle K, between the two parts, N, of the arm L.

To this arm, and on the pintle K of the same, is hung another cross-arm, O, to which, in connection with the part P to the bracket-arm L, hereinbefore referred to, bars, Q, are hung, that are substitutes for the hames-straps of ordinary harness.

The strap I is continued under the bracket-arm and toward the saddle R, where it is hung to a loop, S, at one end of a pintle, T, arranged to move within a bracket-arm, U, of such saddle.

V, a spring, coiled around the pintle T.

W, a loop, of saddle-bracket arm U, to which is hung the front end of the crupper-strap X.

The saddle R is made in two parts, hinged together at the centre line Y, the pintle T, hereinbefore referred to, forming the centre of such hinge.

Z, a strap, hung to loop W, by the pulling of which the several pintles, hereinbefore referred to, are drawn, and thus the several parts of the harness allowed to fall apart or along their lines where hinged or hung together, as is obvious without any further description.

I claim as new, and desire to secure by Letters Patent—

The combination of the bridle C, plates D and G, hames-straps O, bars Q, and saddle R, with the looped pintles E K T and straps I Z, all arranged and operating as herein described, for the purpose specified.

ROBERT O'BRIEN.
